(57) **CLAIM**

We claim the ornamental design of a humeral stem, as shown and described.

DESCRIPTION

FIG. 1 is a plain front view thereof the humeral stem showing my new design.

FIG. 2 is a plain inner side view thereof the humeral stem showing my new design.

FIG. 3 is a plain outer side view thereof.

FIG. 4 is a plain top view thereof the humeral stem showing my new design.

FIG. 5 is a perspective front view thereof.

FIG. 6 is a perspective inner side view thereof.

FIG. 7 is perspective outer side view thereof.

FIG. 8 is perspective bottom view thereof; and,

FIG. 9 is perspective top view thereof.

The broke line showing the environment in the figures are for illustrative purposes only and form no part of the claimed design.
